UNITED STATES PATENT OFFICE

ANTONIO ZICKE, OF SAN FRANCISCO, CALIFORNIA

DESIGN FOR AN ELECTRIC SIGN

Application filed April 26, 1932. Serial No. 43,614. Term of patent 3½ years.

To all whom it may concern:

Be it known that I, ANTONIO ZICKE, a citizen of the United States of America, residing at San Francisco, county of San Francisco and State of California, have invented a new, original, and ornamental Design for Electric Signs of which the following is a specification, reference being had to the accompanying drawing, forming a part thereof.

Figure 1 is a front elevation of my sign with the background board broken away. Figure 2 is a diagrammatic cross-sectional view on a reduced scale showing my sign mounted upon the back-board.

I claim:—

The ornamental design for an electric sign substantially as shown.

ANTONIO ZICKE.
